(57) **CLAIM**

The ornamental design for a motorcycle, as shown and described.

DESCRIPTION

FIG. 1 is a top, front, and right side perspective view of a motorcycle, showing my new design;

FIG. 2 is a bottom, rear, and left side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of a portion labelled 9 in FIG. 1;

FIG. 10 is an enlarged view of a portion labelled 10 in FIG. 1;

FIG. 11 is an enlarged view of a portion labelled 11 in FIG. 2;

FIG. 12 is an enlarged view of a portion labelled 12 in FIG. 3;

FIG. 13 is an enlarged view of a portion labelled 13 in FIG. 4; and,

FIG. 14 is an enlarged view of a portion labelled 14 in FIG. 8.

The broken lines in the drawings depict portions of the motorcycle that form no part of the claimed design.

The dash dot dash lines in FIG. 1, FIG. 2, FIG. 3, FIG. 4, FIG. 8, FIG. 9, FIG. 10, FIG. 11, FIG. 12, FIG. 13 and FIG. 14 are for the purpose of depicting the boundary of the enlarged view and form no part of the claim.

1 Claim, 14 Drawing Sheets
